UNITED STATES PATENT OFFICE.

FRANCIS ENDICOTT, OF CLIFTON, ASSIGNOR TO CHARLES F. IMBRIE, OF NEW YORK, N. Y.

FLY-BOOK.

SPECIFICATION forming part of Letters Patent No. 258,393, dated May 23, 1882.

Application filed July 6, 1881. (No model.)

To all whom it may concern:

Be it known that I, FRANCIS ENDICOTT, of Clifton, in the county of Richmond and State of New York, have invented certain useful 5 Improvements in Fly-Books, of which the following is a specification.

My invention relates to books or holders used for carrying fishing-flies and snelled hooks, and has the object to prevent the flies from 10 becoming tangled, and to allow for their convenient insertion and removal.

Figure 1 is a face view of an open fly-book of the improved construction. Fig. 2 is a section on line $x\ x$ of Fig. 1, showing the manner 15 in which the retainers are secured to the leaves; and Fig. 3 is a section on line $y\ y$ of Fig. 1.

Similar letters of reference indicate corresponding parts.

The book, consisting of cover A and leaves 20 B, is of usual construction, except as herein-after specified. At the top or bottom of each leaf B metal clips a are attached, which clips are similar to those heretofore used, and at the opposite end of the leaf are the spring-retainers b . These consist preferably of spiral 25 springs attached at one end by a thread sewed into the material of the leaf, and formed at the other end with an eye or hook, c , for attachment of the snell. A thread, d , preferably of silk-worm gut, passes through each 30 spring b , and through the leaf to and through the spring on the opposite side. These serve

to hold the springs in place when the flies are detached, and at the same time allow the springs to stretch. At the edges of the leaves 35 B a re-enforcing strip, e , of metal or other suitable material, is secured between the two sheets of material of which the leaf is formed. This strip serves to strengthen the leaves at the places most liable to wear, and also prevents 40 them from buckling by the tension of the spring-retainers.

In use the hooks are caught beneath the clips a , as shown, and the snells shown at f are caught upon the retainers b . The springs are 45 thus stretched and retain the snells taut, so that they are held securely, and may be readily removed as wanted.

With these devices a large number of flies or snelled hooks can be carried in the book 50 with great convenience.

If desired, the clips and retaining-springs may be alternated on each end of the leaf, and intermediate retainers applied for shorter snells.

Having thus described my invention, I claim 55 as new and desire to secure by Letters Patent—

In fly-books, the threads d , in combination with retainers b , as and for the purposes described.

FRANCIS ENDICOTT.
